UNITED STATES PATENT OFFICE.

CHARLES A. VERSCHOOR, OF ANN ARBOR, MICHIGAN, ASSIGNOR TO PRECISION PRODUCTS COMPANY, OF ANN ARBOR, MICHIGAN, A CORPORATION OF DELAWARE.

DESIGN FOR A RADIOCABINET.

Application filed June 19, 1926. Serial No. 18,094. Term of patent 3½ years.

To all whom it may concern:

Be it known that I, CHARLES A. VERSCHOOR, a citizen of the United States, residing at Ann Arbor, in the county of Washtenaw and State of Michigan, have invented a new, original, and ornamental Design for a Radiocabinet of which the following is a specification, reference being had to the accompanying drawing, forming a part thereof.

The figure is a view in perspective showing my new design.

I claim:

The ornamental design for a radiocabinet substantially as shown.

CHARLES A. VERSCHOOR.
